(57) **CLAIM**

The ornamental design for a dual straw container insert, as shown and described.

DESCRIPTION

FIG. 1 is a bottom perspective view of a dual straw container insert, showing my new design;

FIG. 2 is a top view thereof;

FIG. 3 is a first side view thereof;

FIG. 4 is a second side view thereof;

FIG. 5 is a third side view thereof;

FIG. 6 is a fourth side view thereof; and,

FIG. 7 is a bottom view thereof.

1 Claim, 3 Drawing Sheets
